(57) **CLAIM**

I claim the ornamental design for a bag scooper, as shown and described.

DESCRIPTION

FIG. 1 is a perspective view taken from the top front of a bag scooper of my new design, the bottom front perspective view being identical thereto;

FIG. 2 is a right side elevational view thereof;

FIG. 3 is a left side elevational view thereof;

FIG. 4 is a front elevational view thereof; and,

FIG. 5 is a back elevational view thereof.
